US00D773491S

(12) United States Design Patent (10) Patent No.: US D773,491 S
Ahdritz et al. (45) Date of Patent: * Dec. 6, 2016

(54) DISPLAY SCREEN WITH A GRAPHICAL USER INTERFACE

(71) Applicant: Kobalt Music Group Limited, London (GB)

(72) Inventors: Willard Bengt Anders Ahdritz, Scarsdale, NY (US); Simon Thomas Dennett, New York, NY (US); Raphael Willy Robert Amselli, Essex (GB); James Piers Fitzherbert-Brockholes, Isle of Wight (GB); Richard Alwin Curtis Thompson, London (GB)

(73) Assignee: Kobalt Music Group Limited, London (GB)

() Term: 14 Years

(21) Appl. No.: 29/449,902

(22) Filed: Mar. 15, 2013

(51) LOC (10) Cl. 14-04

(52) U.S. Cl. USPC D14/486

(58) Field of Classification Search

USPC D14/485-495
 CPC ... G06F 3/0481; G06F 3/0482; G06F 3/04866

(57) CLAIM

The ornamental design for a display screen with a graphical user interface, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever. The following notice applies: © 2013, Kobalt Music Group Limited.

FIG. 1 is a front view of a display screen with a graphical user interface showing our new design;

FIG. 2 is a second embodiment thereof;

FIG. 3 is a third embodiment thereof; and,

FIG. 4 is a fourth embodiment thereof.

The broken lines showing the display screen and remainder of the graphical user interface form no part of the claimed design.

1 Claim, 4 Drawing Sheets

FIG. 1

FIG. 3

The screenshot shows the Kobalt Music Group Limited software interface. At the top, the logo 'K Kobalt' and the tagline 'MUSIC SERVICES FOR THE 21ST CENTURY' are visible. The top navigation bar includes links for HOME, CATALOGUE, REPORTING, CREATIVE, MY SETTINGS, and HELP, along with a 'LOGOUT' button. Below the navigation bar, there are links for WORKING BALANCE, ORDER ADVANCE, AUTOMATION, and ACTIVITIES.

The main content area is divided into several sections:

- HOME: A black bar with 'HOME' and 'CLIENT SELECTION' (set to 'PUBLISHING CLIENT NAME').
- ACTION CENTRE SUMMARY: A table showing the following data:

	TOTAL	URGENT	PAT	10MTHS	2YRNS
INCOMPLETE WORKS	10	0	0	1	7
PENDING PAYMENT	100	0	0	1	98
PUBLISHING CLNS	4	1	0	0	4
ADM PAYMENT REQUEST	32	4	2	0	30

Buttons for 'DETAILS' and a right-pointing arrow are at the bottom.
- ACTIVITY FEED: A list of activity items:
  - RECEIVED PAYMENT FOR WORK 1 IN NEW YORK
  - ACQUISITE CLASS HAS BEEN OPENED FOR WORK 1 IN USA
  - ACQUISITE CLASS HAS BEEN OPENED FOR WORK 1 IN ITALY
  - ACQUISITE CLASS HAS BEEN OPENED FOR WORK 1 IN FRANCE
  - ACQUISITE CLASS HAS BEEN OPENED FOR WORK 1 IN USA
  - ACQUISITE CLASS HAS BEEN OPENED FOR WORK 1 IN USA
  - ACQUISITE CLASS HAS BEEN OPENED FOR WORK 1 IN CANADA

Buttons for 'DETAILS' and a right-pointing arrow are at the bottom.
- CATALOGUE SEARCH: A search bar with placeholder text 'WORK / PUBLISHING / PRODUCTION / ALL' and a 'SEARCH' button. Below the search bar is an 'ADVANCED SEARCH' button.
